[57] CLAIM

The ornamental design for a notebook with snap closure, as shown and described.

DESCRIPTION

FIG. 1 is a front perspective view of a first embodiment of a notebook with snap closure showing my new design;

FIG. 2 is a front elevational view;

FIG. 3 is a left side elevational view;

FIG. 4 is a right side elevational view;

FIG. 5 is a top plan view, the bottom view being a mirror image thereof; and

FIG. 6 is a rear elevational view thereof;

FIG. 7 is a front perspective view of a second embodiment of my new design;

FIG. 8 is a front elevational view of FIG. 7;

FIG. 9 is a left side elevational view of FIG. 7;

FIG. 10 is a right side elevational view of FIG. 7;

FIG. 11 is a top plan view of FIG. 7, the bottom view being a mirror image thereof; and,

FIG. 12 is a rear elevational view of FIG. 7.
